UNITED STATES PATENT OFFICE.

EDOUARD HERCUL ROUSSEAU, OF GRANBY, QUEBEC, CANADA.

BUCKBOARD-WAGON.

SPECIFICATION forming part of Letters Patent No. 355,215, dated December 28, 1886.

Application filed December 4, 1885. Serial No. 184,699. (No. model.) Patented in Canada July 2, 1885, No. 21,955.

To all whom it may concern:

Be it known that I, EDOUARD HERCUL ROUSSEAU, a subject of Our Sovereign Lady Queen Victoria, Queen of the United Kingdom of Great Britain and Ireland, &c., residing at the village of Granby, in the county of Shefford and Province of Quebec, Dominion of Canada, have invented some new and useful Improvements in Buckboard and Buggy Wagons, (for which I have received Letters Patent in the Dominion of Canada, No. 21,955, dated July 2, 1885;) and I do hereby declare that the following is a full, clear, and exact description of the invention, which will enable others skilled in the art to which it appertains to make the same, reference being made to the accompanying drawings, in which—

Figure 1 is a downward view upon the wagon-gear of my said invention. Fig. 2 is an isometrical projection of the said invention.

The first part of my invention consists in the method of the attachment to the seat of the slats which form the board in "buckboard-wagons." This method is an improvement on the old plan of carrying these straight through from the rocker to the hind axle of the wagon. This method also combines the advantages of side springs with buckboard-gear, with none of their drawbacks.

The second part of my invention is the attachment of the foot-rod, which, balancing the springs of the gear, prevents that jar upon the foot-rod which causes numbness in the feet and ankles of persons riding in an ordinary buckboard-wagon.

A, Fig. 1, is a frame of hard wood. It is joined at the corners, as shown. On the frame the seat rests, being hinged in front.

To the frame are fastened slats *a*, in front and behind the seat. Their outside ends are straight. Their inside ends are bent upward, where they are attached to the seat-frame, and where they are fastened by bolts and screws, as shown. The two outside bolts run through the seat-frame, and thereby strengthen it. The outside ends are bolted to the rocker and the axle.

Beginning at the rocker on each side end, bolted to it under the slats at the sides are two steel springs one-fourth of an inch thick by one and one-half inch wide, *B B*, Fig. 2. These springs follow the bend of the slats a little way, and then an independent curve brings

them under the seat-frame. They then take the curve of the slats behind the seat-frame, and are fastened with bolts to the axle. They act to strengthen the gear, which can sustain any suitable weight without breaking, for when the bent pieces—themselves springs—are pressed downward by any weight or sudden impact upon the seat the steel springs bend also. If the weight or force of impact be strong enough to straighten the steel springs, they then bear in a straight line from their bolted ends and hold the rocker and axle, so that the wooden springs can be bent no more. On top of these bent pieces, in front of the seat-frame, rests the foot-rod attachment. This is the second part of my invention. It is made up of steel springs one-fourth of an inch thick by one and one-fourth inch wide, *c c*, Figs. 1 and 2. These springs follow the direction of the curve of the bent pieces a little way, and then rise above the bent pieces, causing their front ends to play freely. To these are fastened cross-slats *d d*, Figs. 1 and 2. At the front of these is fastened the foot-rod *D*, and the dash is also fastened onto the two outside springs, which project two inches longer than the other two.

I make no claim to slats in buckboard-gear ordinarily used, for I am aware that their use in such gear is not new; but

What I claim as my invention, and desire to secure by Letters Patent, is—

1. The combination, in a buckboard, of the steel springs *B B*, independent of the seat, secured at one end to the rocker and at the other to the hind axle, with the bent pieces *a a*, substantially as shown and described.

2. The combination, in a buckboard, of the springs *c c* and cross-slats *d d*, secured to said springs *c c*, with the bent pieces *a a*, substantially as set forth.

3. In a buckboard-wagon, the combination of the springs *B B*, bent pieces *a a*, and seat-frame *A*, with the springs *c c* and foot-bar *D*, all arranged substantially as and for the purpose shown and described.

Granby, Province of Quebec, this 16th day of October, 1885.

EDOUARD HERCUL ROUSSEAU.
